UNITED STATES PATENT OFFICE.

MICHEL D. LUEHRS, OF CLEVELAND, OHIO.

MACHINE FOR TURNING TAPERS.

SPECIFICATION forming part of Letters Patent No. 371,691, dated October 18, 1887.

Application filed January 8, 1887. Serial No. 23,742. (No model.)

To all whom it may concern:

Be it known that I, MICHEL D. LUEHRS, a citizen of the United States, residing at Cleveland, county of Cuyahoga, and State of Ohio, 5 have invented certain new and useful Improvements in Taper-Turning Machines; and I do hereby declare the following to be a description of the same, and of the manner of constructing and using the invention, in such 10 full, clear, concise, and exact terms as to enable any person skilled in the art to which it appertains to construct and use the same, reference being had to the accompanying drawings, forming a part of this specification, the 15 principle of the invention being herein explained and the best mode in which I have contemplated applying that principle, so as to distinguish it from other inventions.

This invention has for its object the construction of a turning-machine that shall be automatic in its operation, and thus dispense with much of the expense which has heretofore been required for labor in the ordinary tapering-machines.

25 The principle employed in opening the dies for cutting the taper is the same already patented to me in United States Letters Patent No. 324,946, dated August 25, 1885, for bolt-cutter heads. In the ordinary form of tapering machine but one tool is used to do the work, and the cutting-edge of this tool equals the length of the taper to be cut. From this it is apparent, first, that a great power must be exerted to cut the taper, as the knife sometimes has a bearing its entire length, and, second, that if, as often happens, the axle or other work to be tapered is of uneven hardness that part of the knife coming in contact with the harder portions will become dull and 35 nicked, when it of course no longer cuts an even taper and must be reground its entire length before it is of further use. In my tapering-machine I use four small dies for cutting. These are easily removed, cheaply sharpened, 45 and of small cost to renew when worn out.

My invention cheapens the cost of the working machine by lessened first cost for dies; by making it automatic, thus reducing the cost for labor; by reducing the amount of power 50 required to do the work, as the dies, having but small bearing, do not require the power to run them the old style does; by reducing cost of sharpening and renewing dies; by doing away with the necessity for skilled mechanics

to set the tools for cutting the paper, as in my 55 machine a cheap boy can place the dies in position, and from that time until the work is finished the machine works automatically, thus enabling one man to run three or four machines.

Referring to the drawings, Figure 1 is a vertical longitudinal sectional view. Fig. 2 is a plan view. Fig. 3 is an end elevation. Fig. 4 is an elevation on line $z z$ of Fig. 1. Fig. 5 is an edge view of the die.

A is the driving cog-wheel, which drives shaft B, which is connected to barrel C in the usual manner, and revolves said barrel C and die-ring D. Hard-metal bearing blades d are fitted into the periphery of barrel C, and have 70 bearing against corresponding bearing-blades, d' , fitted in the inner periphery of die ring D. The die-ring is provided with inclined radial T-shaped slots e , into which are fitted the heads v of the dies E, these heads having the 75 same inclination as the slot. The barrel is also provided with slots f , through which the bodies of the dies are fitted. On the face of the barrel is a cap, g , to hold the dies in place. The die ring surrounds the barrel and is fitted loosely on it, being provided, as above noted, with bearing-blades to decrease the 80 friction.

Around the die-ring is fitted a yoke, F, which permits the die-ring to revolve within it, and 85 has bearing on face G of the machine-bed. Rigidly secured to the yoke are horizontal rods H, on either side of the die-ring, which reciprocate the die-ring on the barrel. The opposite ends of these rods H are fitted in posts h , 90 rigid with feed carriage I. Sleeves i are adjustably secured on either side of the posts with some allowance for play. The feed-carriage is also provided with vise-jaws J, for holding the working metal. These jaws are 95 moved by pinion j , meshing with cog k . The pinion is actuated by hand-wheel l , and its shaft is provided with right-hand and left-hand threads, so as to keep the jaws of the vise at equal distance from the center.

The outer face, G, of the machine is provided on one side with rack m , and on the other with rack m' , which respectively mesh with pinions o o' , actuated by hand-wheels p p' , attached to feed-carriage, thus furnishing a reciprocating hand mechanism for said carriage. On the under side of the barrel, and extending from the driving-wheel to the end of the feed-

carriage, is a shaft, K, secured at its one end to a cog-wheel, q, meshing with wheel q', attached to main shaft B, and of size equal to wheel q', thus making as many revolutions as the main shaft. The opposite end of this shaft is threaded and passes under the feed-carriage, to which it is connected and disconnected by clutch-nuts s s', actuated by lever r, moving pins t t', to which the nuts are connected in slots u u'. The heads v of the dies E are formed separate from the dies and secured to the same in any suitable manner, as by a screw, w. Between the head and die is placed a piece of packing, x, in order to fit the die to its place and make the different dies of equal length. When the dies are worn, they may be removed from the head, turned end for end, sharpened, and re-packed. The screw serves as a regulator, for by it the die may be drawn up or loosened in the head.

The operation of the machine is as follows: The metal to be tapered is placed in the vise-jaws, and by means of the hand-wheel l the jaws are tightened. The feed-carriage is moved toward the die-ring by means of the hand-wheels p p' and connecting mechanism, and the sleeves are rigidly fastened on rods H at distances from die-ring suitable to the size of work to be done—that is, if the work be large the die-ring should be forced outward and the dies will be moved from one another and increase the initial diameter of the taper—and in this case the distance from the post to the die ring will be lessened. The sleeves between the posts and die-ring having been suitably adjusted to this end and the sleeves on the opposite sides of the posts being secured a short distance from the posts, that when the taper is finished the feed-carriage may be moved back somewhat with the taper before the die-ring is moved, and thus free the taper from the die-ring, the lever r is moved and causes nuts s s' to clutch shaft K. The main shaft B is now revolved, which causes the dies to revolve with it, and also the shaft K, which gradually moves the work-carriage toward the die-ring. As the carriage moves, the rods H are caused to move, and, being rigidly secured at one end to the yoke, which is in turn secured to the die-ring, move the die-ring in the same direction and to the same extent as the work-carriage moves. The heads of the dies are fitted in the inclined radial slots of the die-ring, and as the die-ring is gradually forced away from the advancing work-carriage the distance between the cutting-ends of the dies is increased, and thus the work is tapered.

What I claim is—

1. In a taper-turning machine, the combination, with dies, die-ring, and barrel, the two latter having radial slots in which the dies have bearing and being connected to a rotary shaft, of a work-carriage connected to a rotary shaft and connected by intermediate pieces with said die-ring, substantially as set forth.
2. In a taper-turning machine, the combination,

with a die-ring provided on its inner peripheral face with a series of circumferential hard-metal bearings, of a barrel having on its outer periphery a series of hard-metal bearings, the corresponding members of the two series being in contact with each other, substantially as set forth.

3. In a taper-turning machine, the combination, with dies, die-ring, and barrel, the two latter having radial slots in which the dies have bearing, said die-ring having lateral flanges, of a work-carriage and rods connecting said carriage and flanges, substantially as set forth.

4. In a taper-turning machine, the combination, with dies, die-ring, and barrel, the two latter having radial slots in which the dies have bearing, said die-ring being provided with flanges, of a work-carriage provided with upright supports having tubular bearings, and rods connected at one end with the flanges and having bearing at their opposite ends in said supports, substantially as set forth.

5. In a taper-turning machine, the combination, with dies, die-ring, and barrel, the two latter having radial slots in which the dies have bearing, said die-ring secured to a primary rotary shaft, of a work-carriage adjustably secured to a secondary rotary shaft and connected by intermediate connection with said die-ring, said two shafts being geared together, substantially as set forth.

6. In a turning-machine, the combination, with a barrel having die-slots and a die-ring having inclined radial slots, of a die, and a die-cap, and a longitudinally-adjusting device connecting said two latter parts and adapted to adjust said die longitudinally relative to the die-cap, substantially as set forth.

7. In a turning-machine, the combination, with a barrel having die-slots and a die-ring having inclined radial slots, of a die, a cap, and a longitudinally-adjusting device connecting said two latter parts together, and packing intermediate of the die-cap and die, substantially as set forth.

8. In a taper-turning machine, the combination, with dies, die-ring, and barrel, the two latter having radial slots in which the dies have bearing, of a work-carriage, and rods secured to said die-ring and said work-carriage, substantially as set forth.

9. In a taper-turning machine, the combination, with dies E, die-ring D, and barrel C, the two latter having radial slots in which the dies have bearing, of work-carriage I, provided with upright posts h, and rod H, secured at its two ends, respectively, with yoke F and said post h, substantially as set forth.

In testimony that I claim the foregoing to be my invention I have hereunto set my hand.

MICHEL D. LUEHRS.
